UNITED STATES PATENT OFFICE.

DANIEL F. SCHEAF, OF DAYTON, OHIO.

IMPROVED APPARATUS FOR GENERATING GAS.

Specification forming part of Letters Patent No. **73,124**, dated January 7, 1868.

To all whom it may concern:

Be it known that I, DANIEL F. SCHEAF, of Dayton, in the county of Montgomery, and in the State of Ohio, have invented certain new and useful Improvements in Self-Generating Gas-Machines; and do hereby declare that the following is a full, clear, and exact description thereof, reference being had to the accompanying drawings, and to the letters of reference marked thereon.

In the annexed drawings, making part of this specification, A represents the vessel or tank, which contains the gasoline of which the gas is to be made. The gasoline is introduced to the tank through a funnel-shaped pipe, J, said pipe being provided with a suitable stop-cock.

C represents a pipe, which connects with the tank A near its bottom, and then, passing into a stove, B, is coiled as many times as may be desirable, and then returned to the tank A near its top. This pipe C is provided with a stop-cock, which has connected to its outer end a lever, P, one end of which is weighted.

F represents a gas-reservoir, which is made in the usual way. This reservoir is connected to the tank A by means of a pipe, H, which passes from the top of the tank to the under side of the reservoir.

G represents a pipe, which connects to the tank A at its top, and is for the purpose of conveying away the gas from said tank to be burned. A rod projects from the center of the top of the gas-reservoir, and to the outer end of this rod a chain or cord, N, passes down and around a pulley, O, and thence to one end of the lever P. The stop-cock of pipe C is operated in one direction by the weight on the end of lever P, and in the other by the chain N, which is moved by the rising of the top of the reservoir. A perforated diaphragm, E, is inserted in the tank A near its upper end. The upper side of this diaphragm is provided with a packing of cotton or wool, or other suitable substance, for filtering the gasoline and gas. When the gasoline is poured into the tank it must pass through this diaphragm with its packing before it can enter the pipe C to pass to the stove.

In making gas with this machine, the ma-

terial is allowed to pass from tank A through pipe C at the bottom of the tank, and thence through stove B, and thence back again in the form of gas to the upper part of the tank. The material is converted into gas by the heat of the stove, and the gas, after passing through the filtering material upon diaphragm E, enters pipe H, and is conducted into reservoir F. When the reservoir becomes full, the rod attached to its top, acting upon chain N and lever P, closes pipe C, so as to prevent the further manufacture of gas. When it is desired to use the gas, the stop-cock of pipe G is opened, and the gas immediately returns through pipe H into tank A, and from said tank through pipe G to the burners which connect with it. By again passing the gas when once made into tank A, in its passage to the burner, it burns with more brilliancy.

In addition to the mode just described, I employ another mode of making gas. I use a bellows, K, which connects with the tank A by means of a pipe, L. This bellows serves to force air through the gasoline, which carbonizes it for use. I may thus use this apparatus either with or without a stove, and make excellent gas for family use or for consumption on a greater scale.

Having thus fully described my invention, what I claim as new, and desire to secure by Letters Patent, is—

1. The arrangement of the tank A, pipe C, and stove B, in such a manner that the made gas is passed back through the oil-tank, the various parts being constructed and operating substantially as set forth.

2. The arrangement of the receiver-top with chain N, lever P, and pipe C, provided with a stop-cock, in such a manner that the flow of oil to the generator is regulated by the rise and fall of the receiver-top, substantially as and for the purposes specified.

In testimony that I claim the foregoing I have hereunto set my hand this 15th day of August, 1867.

DANIEL F. SCHEAF.
